UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

TRIMMING MACHINE.

Application filed June 18, 1917, Serial No. 175,421. Renewed November 19, 1920. Serial No. 425,291.

This invention relates to machines for operating on boots and shoes, and is illustrated, by way of example, as embodied in a machine for trimming the edges of the soles of shoes.

The soles of a large proportion of shoes have three distinct profiles, one in the forepart, another at the inner edge of the shank, and the third at the outer edge of the shank.

10 The inner edge of the shank is usually undercut, whereas the outer edge is usually, if not always, square and differs from the edge of the forepart in that the latter is slightly beveled at the tread surface and in 15 some cases has one or two ornamental beads. Consequently, three different cutters are required to trim the edge of the sole of every shoe which is to have the aforesaid characteristics.

20 For reasons known to those conversant with manufacturing conditions it has not heretofore been feasible to perform all three of the aforesaid trimming operations with one handling of a shoe. This has been due 25 to the fact that no way, so far as I know, has heretofore been discovered to include three cutters in a single organization without retarding production, militating against high-grade work, or subjecting the operatives 30 to danger of injury by one or more of the cutters. Still, it has long been appreciated that it would be desirable to perform these three operations with one handling of a shoe if they could be performed 35 without increasing the risk of injury and without retarding production or increasing the difficulty of turning out high-grade work. Accordingly, an object of this invention is to provide an improved organization 40 by which all three of these or analogous operations may be advantageously performed with only one handling of the shoe.

An edge-trimming operation requires 45 great skill, and it is necessary to arrange the cutters so that the operative may present the shoe to them with the least possible muscular effort, since the quality of the work depends not only upon the accuracy of the operative's eye and judgment but also 50 upon the skill with which he manipulates the shoe. These considerations require arranging the cutters so that the operative may remain standing or sitting, as the case may be, in one position where he can readily 55 manipulate the shoe at different stations

for successive operations without losing sight of the working locality, without sacrificing control or safety and without feeling undue fatigue or strain.

In view of these considerations, and to 60 attain the aforesaid object in accordance with a feature of the invention, the illustrated machine comprises, as usual, two cutter shafts one of which carries a cutter for trimming the forepart and the other 65 of which carries a cutter for trimming the inner edge of the shank, but the latter shaft also carries a third cutter which may be used to trim the outer edge of the shank. Furthermore, since two of the cutters are 70 carried by one shaft and each of them must clear the shoe while the other is operating, to provide for mutual exclusiveness of operation, the invention provides for relative 75 movement thereof in one direction to afford such clearance and relative movement in the opposite direction to locate these two cutters so close to each other that although the shoe occupies one station for operation by one of them, and another station for 80 operation by the other, these stations will be so close to each other as to relieve the operative from all difficulty of presenting the shoe at three different stations.

Again, while the aforesaid relative movement of the two coaxial cutters provides 85 for clearance of the shoe by one of them while the other is operating, clearance by the latter while the one is operating is insured by giving one a relatively large diameter and the other a relatively small diameter. Thus, two factors, namely, relative movement of these cutters and a substantial 90 difference in diameter, provide for mutual exclusiveness of operation without appreciably affecting the conditions under which the operative presents the shoe to first one and then the other.

These and other features of the invention 100 comprising various combinations and arrangements of parts will be best understood and appreciated from the following description of a preferred embodiment thereof selected for purposes of illustration and shown in the accompanying drawings, in 105 which

Figure 1 is a side elevation partially broken away of the machine illustrating the use of one cutter,

Fig. 2 is a rear elevation, and

110

Fig. 3 is a detail of the machine as shown at Fig. 1 illustrating the use of another cutter.

The main frame 10 of the machine carries a shaft 12. This shaft is compound and comprises an inside shaft 14 and a preferably concentric sleeve 16 which has a longitudinal slot at 18. The sleeve 16 fits within the bearings 20 which abut upon the pulley 22. This pulley is pinned to the internal shaft 14 by a pin 24 which passes through the longitudinal slot 18 in the sleeve 16. The sleeve 16, therefore, can be moved longitudinally of the internal shaft 14, but is driven with it by the engagement of the pin 24 with the edge of the slot 18. Upon the end of the shaft 14 is a shank cutter 26 and upon the end of the sleeve 16 is mounted a shank cutter 28. The shank cutter 26 is of small diameter and is shown of curved profile and is shaped to undercut the inside edge of the shank of the shoe. The cutter 28, as shown, is of larger diameter than the cutter 26 and may have a straight profile, to impart a square cut to the outside edge of the shank.

The sleeve 16 projects beyond the end of the internal shaft 14 and projects from the back of a machine. It has mounted on it a collar 30 which is engaged by a shifting yoke 32 of any desired construction mounted upon the end of a bell crank lever 34 pivoted on a bracket 35 mounted on the main frame. The other end of the bell crank has a handle 36 which can be moved by the operator. When the handle is moved down the bell crank 34 will move the sleeve 16 toward the front of the machine carrying the cutter 28 to the full line position shown in Fig. 1. When the handle 36 is raised the sleeve 16 will be retracted and the cutter 28 will be moved to the dotted line position shown in Fig. 1.

When it is desired to trim the outside of the shank the shoe is placed in the position shown in Fig. 1 with the shank in engagement with the cutter 28. This cutter being of larger diameter than the cutter 26 and the upper of the shoe overhanging the shank very little upon the outside, the cutter 26 will not strike the upper of the shoe while the cutter 28 is trimming the shank. When the inside of the shank is to be trimmed, the cutter 26 is used and it will be clear from the dotted lines of Fig. 3 that the cutter 28, if left in that position, would scar the heel breast as the cutter 26 approaches the rear end of the shank because of its greater diameter. This is avoided by moving the cutter 28 back to the full line position in Fig. 3 where it will clear the shoe.

The upper part of the machine frame, as shown, carries a shaft 38 upon which may be mounted the forepart cutter. In the operation of the machine the operator will

trim one side of the shank of the shoe on the cutter 26 as shown in Fig. 3, the cutter 28 being drawn back out of the way, will then run around the forepart with the forepart trimmer and will then move the cutter 28 forward to its operative position and trim the outside of the shank. Although the station at which the shoe is presented for operation by the cutter 28 is not quite the same as that in which it is presented to the cutter 26, the difference is scarcely perceptible to the operative, since the distance between these stations is reduced to a negligible magnitude by shifting the cutter 28 to its operating position. If it is desired to shift the cutter 28 only once for each shoe it may be left in its operative position for the next shoe, in which case the operative will use it before he uses the cutter 26, thus using these two cutters in reverse order for successive shoes but in the same order for alternate shoes.

My compound driving shaft presents a mechanical feature of considerable importance. Inasmuch as the inside shaft 14 and the sleeve 16 rotate together, they balance in rotation as one rotating member. Absolute concentricity of the two, considered separately, is therefore not of great importance. The two parts are carefully fitted together, the outside of the sleeve and the projecting end of the shaft 14 are then concentrically ground, and the compound shaft and cutters will then run true even if the enclosed portion of the shaft 14 is off center. This feature is of considerable practical importance, as it would be mechanically impossible to produce commercially the concentricity which would be requisite if the two cutter carrying members were to rotate independently.

The presence of the slot 18, which unbalances the system to some extent, can be compensated for by slotting the other side of the sleeve, as shown at 40, after the grinding, the amount of metal cut away being such as to balance the shaft and cutters perfectly.

Having described the invention, what I claim as new and desire to secure by Letters Patent of the United States is:—

1. A machine for operating on shoes comprising two tools arranged to operate, each exclusively of the other, on a shoe located at one station for one of them and at another station for the other, and means arranged to shift one of said tools in one direction to clear the shoe while the other is operating and in the opposite direction to reduce the distance between said stations for operation of said one.

2. A machine for operating on shoes comprising two tools arranged to operate, each exclusively of the other, on the edge of the sole of a shoe located at one station for one of them and at another station for the other,

and means arranged to shift one of said tools in one direction to clear the shoe while the other is operating and in the opposite direction to reduce the distance between said 5 stations for operation of said one.

3. A machine for operating on shoes comprising two rotary tools arranged in coaxial relation to operate, each exclusively of the other, on a shoe located at one station for 10 one of them and at another station for the other, and means arranged to shift one of said tools in one direction to clear the shoe while the other is operating and in the opposite direction to reduce the distance between 15 said stations for operation of said one.

4. A machine for operating on shoes comprising two rotary tools of different diameters arranged in coaxial relation to operate, each exclusively of the other, on the edge of 20 the sole of a shoe located at one station for one of them and at another station for the other, and means arranged to shift one of said tools in one direction to clear the shoe while the other is operating and in the opposite 25 direction to reduce the distance between said stations for operation of said one.

5. A machine for operating on shoes comprising two rotary cutters of different diameters arranged in coaxial relation to operate, 30 each exclusively of the other, on the edge of the sole of a shoe located at one station for one of them and at another station for the other, the smaller one of said cutters being shaped to undercut the shank of the sole, and 35 means arranged to shift said cutters rela-

tively one to the other to enable the larger one of said cutters to clear the heel while the smaller cutter is operating and to reduce the distance between said stations for operation of said larger one. 40

6. A machine for operating on shoes comprising two rotary cutters arranged to operate, each exclusively of the other, on the edge of the sole of a shoe located at one station for one of them and at another station for 45 the other, one of said cutters being shaped to undercut the shank of the sole, and means arranged to shift the other one of said cutters in one direction to clear the shoe while said one is operating and in the opposite direction 50 to reduce the distance between said stations for operation of said other.

7. A machine for operating on shoes comprising two rotary cutters of different diameters arranged in coaxial relation to operate, 55 each exclusively of the other, on the edge of the sole of a shoe located at one station for one of them and at another station for the other, the smaller one of said cutters being shaped to undercut the shank of the sole and 60 being maintained at one location, and means arranged to shift the larger one of said cutters axially in one direction to clear the heel of the shoe while the smaller cutter is operating and in the opposite direction to 65 reduce the distance between said stations.

In testimony whereof I have signed my name to this specification.

FREDERICK M. FURBER.
